UNITED STATES PATENT OFFICE.

JAMES K. LANNING, OF BOSTON, MASSACHUSETTS.

STOP-MOTION FOR LOOMS.

1,253,395.

Specification of Letters Patent. Patented Jan. 15, 1918.

Application filed October 2, 1911. Serial No. 652,227.

To all whom it may concern:

Be it known that I, JAMES K. LANNING, a citizen of the United States, and a resident of Boston, in the county of Suffolk and 5 State of Massachusetts, have invented an Improvement in Stop-Motions for Looms, of which the following description, in connection with the accompanying drawings, is a specification, like characters on the drawings 10 representing like parts.

This invention relates to stop motions for looms, and more particularly to warp stop motions therefor.

In order that the principle of the invention may be readily understood, I have disclosed a single embodiment thereof in the accompanying drawings, wherein—

Figure 1 is a view in transverse vertical section of a loom having my invention applied thereto;

Fig. 2 is a detail in vertical transverse section of the lease rods, the drop bars, the feeler coöperating therewith and associated parts;

Fig. 3 is a side elevation of a drop bar preferably employed with and constituting a portion of my invention;

Fig. 4 is a front elevation of the loom shown in Fig. 1;

Fig. 5 is a detail in side elevation of a portion of the stop mechanism;

Fig. 6 is a plan view of one side of the loom and showing a portion of the stop mechanism; and

Fig. 7 is a detail in plan view of a portion of the stop mechanism.

My invention relates more particularly to warp stop mechanism for looms, though in certain aspects thereof it may be embodied 40 in other relations. As herein disclosed, however, I employ in connection with a loom having warp supported drop bars adapted upon warp fault to be positioned in the path of a movable feeler mechanism, connecting 45 means constituting important features of my invention, by which a bunter is interposed in the path of the lay, whereby an indicating drop bar serves to move the shipper lever from its notch, and thereby to shift the belt 50 from the fast to the loose pulley. Preferably and as herein indicated, the parts are so arranged that the loom is stopped upon the backward beat of the lay, but within the scope of my invention the organization of 55 parts may be such as to stop the loom upon the forward beat.

Referring more particularly to the drawings, the frame of the loom is indicated at 1. The loom may be of any suitable type, but preferably is one having lease rods 2—2 60 mounted for oscillating movement upon suitable yokes 3 pivoted at 4 upon suitable brackets 5 connected to the side frames of the loom. The warp threads are divided into two series, as indicated in Fig. 1, passing respectively above and below the lease rods 2. Upon said warp threads and preferably between the lease rods 2 are mounted drop bars 6 guided in their indicating movement by guide bars 7—7 mounted in the said 70 brackets 5. While the drop bars may be of any suitable construction, preferably they are shaped as indicated most clearly in Fig. 3, wherein a bar 6 is represented as provided with an elongated slot 8 for the reception of 75 the corresponding guide bar 7, and with an eye 9 through which the warp thread is passed. Between the slot 8 and eye 9 is a narrow communicating slit 10 which thus provides shoulders 11 at opposite sides of said slit 10, 80 and which shoulders serve to support the drop upon the upper edge of the guide bar 7 when the drop bar has fallen into indicating position. The lower part of the drop bar is provided with an irregularly shaped 85 slot 12, herein shown as of a general key hole form. The drop bar is preferably equipped with the slot 12 of suitable formation, so that the drop bar may be used in warp drawing mechanism. The slot 10 is 90 provided in drop bars which are adapted to have inserted in or used with or acted upon by warp drawing machines. These machines, of construction not herein necessary particularly to describe, customarily grip the drop 95 bars at top and bottom. It would therefore be difficult or impossible to draw in the threads at the eye 9 at the top, because the drop bar is there gripped by the warp drawing mechanism. Therefore, in practice the 100 threads are drawn in through the elongated slot 8, and after the drop bars are taken out of the machine, the threads at once slip into the eye 9 at the upper end thereof. It is necessary to have merely a narrow slit, such 105 as indicated connecting the eye 9 and the slot 8, because the drop bar when the thread breaks should not be permitted to fall far enough to allow the guide bar to contact with the extreme top of the eye 9. In other 110 words, the shoulders 11 serve to support the fallen drop bar upon the upper edge of the

guide bar. It is not desirable to prolong the drop bar at its upper end beyond the eye 9, so as to permit the drop bar to be grasped by the warp drawing machine above the eye 9, because if this expedient were resorted to, there would, when the drop bars are positioned in the loom, be a portion of the drop bar extending above the warps. Such a construction would be contrary to that employed in looms of the well-known Coldwell and Gildard type. The construction referred to is more important in mechanical drops than in electrical drops, because in the latter the drop bar does not customarily fall as far as a mechanical drop. The fall of the latter is such as to cause the shoulders 11 to rest upon the guide bar.

Beneath and between the guide bars 7 I provide a single feeler bar 13, with which 20 coöperates a single feeler 14 mounted in suitable supports 14' preferably driven upon the rocker feeler shaft 15, mounted in the brackets 5, as indicated most clearly in Fig. 4. By providing a single bar 13 I simplify the 25 construction of the parts. Oscillating movement is imparted in any suitable manner to the feeler shaft 15 which moves to and fro beneath the normally positioned drop bars. The path of the feeler is, however, such that 30 it engages an indicating drop bar. The loom stopping movement of the feeler is always toward the bar 13 and said feeler coöperates with both banks of drop bars, so as to press an indicating or misplaced drop 35 bar inwardly toward the bar 13. If a drop bar of either bank falls when the feeler is moving outward with respect to said bank, the feeler blade 14 pushes aside the indicating drop bar, but upon its return movement reengages the same and presses it against the bar 13, so as to stop the feeler blade 14 and other mechanism to be described to stop the loom.

The drive shaft of the loom is indicated 45 at 16 in the several figures. Loose thereon is a cam 17 driven in suitable manner from the drive shaft 16 and at a preferably lower speed. Herein, for the purpose, I have indicated a gear 18 fast upon the drive shaft 50 16 and meshing with a gear 19 fast on a stud 20 mounted in a bracket 21 and having upon its opposite end a gear 22 with which meshes a gear 23 sleeved with the cam 17 loosely upon the drive shaft 16. 55 The cam 17 is provided with a suitable track with which engages a roll 24 upon a lever 25 pivoted at 26 upon a bracket 27 extending from the frame of the loom. In this manner a constant rocking motion at 60 suitable speed is imparted to said lever 25. Obviously, however, any other suitable means for the purpose may be employed.

Upon a stud 28 mounted as indicated in Fig. 5 in one of the side frames of the loom, 65 I mount two lever arms 29 and 30 having

interengaging clutch formations 31, 32, which when said arms 29, 30 are rocked in unison are in the interengaging position indicated in Fig. 5. The free end of the arm 30 is pivotally connected by a link 33 to 70 the free end of the lever 25, and the free end of the arm 29 is similarly connected by a link 34 with the feeler shaft 15, preferably by a pin and slot connection 35, as indicated. Obviously, the continuous oscillation of the lever 25 is imparted through the link 33 to the lever arms 30 and 29, the former of which always partakes thereof. The lever arm 29 being connected by link 34 to the single feeler 14 and adapted to be 75 stopped by an indicating drop bar, is held stationary when the indicating drop bar is pressed against the bar 13. The lever arm 30 and the lever arm 29 are loose upon the stud 28. Therefore, when the rocking movement of the arm 29 is stopped by an indicating drop, the continued rocking movement of the arm 30, by reason of the clutch formation 31, 32 of said arms, imparts lateral movement to the arm 30 and its head 80 32 along the stud 28.

Pivoted at 36 upon a bracket 37 upon the frame of the loom is a lever 38, one end whereof (which may be forked if desired) is adapted to contact with the clutch head 95 32 of the arm 30. A coiled spring 40 interposed between said lever arm 38 and the bracket 37 tends normally to force the clutch head 32 toward the clutch head 31. The opposite arm 41 of the lever 38 extends, as 100 indicated most clearly in Fig. 1, to a point directly underneath a bunter 42 pivoted at 43 upon a lever 44 pivoted at one end upon a bracket 45 upon the frame of the loom. Said bunter may, if desired, be provided with an adjusting screw 46 adapted to receive the impact of the lay 47, as indicated in Fig. 1. The lifting movement of the lever arm 41, through the sliding movement of the clutch head 32 upon indicating 110 movement of the drop bar, lifts the bunter 42 into the path of the lay 47. Normally the bunter 42 is positioned beneath the path of movement of the lay 47 so as not to be impinged upon thereby. When, however, the 115 bunter is lifted as described into the path of the lay, the continued movement of the lay upon its backward beat swings the lever 44 to the left viewing Fig. 1. The lower end of said lever 44 is pivotally connected 120 by a link 48 to the shipper lever 49, as indicated most clearly in Figs. 1 and 6, so that the described movement of the lever 44 forces the shipper lever from its retaining notch, and thereby effects the shifting of 125 the belt from the fast to the loose pulley in the customary manner.

Obviously, if desired, the spring 40 may be wholly eliminated and the weight of the lever 38 be relied upon to return the sliding 130

clutch head 32 into interengagement with the clutch head 31.

It will be observed that with the exception of the spring 40, which obviously may be omitted, the stop mechanism herein disclosed dispenses wholly with springs to move the parts. Moreover, the bunter or dog 41 remains stationary at all times until it is lifted into the path of the lay upon the falling of a drop bar.

As previously stated, the stop motion may be effective to stop the loom upon the forward beat of the lay by so arranging and positioning the dog or bunter 42 that it is in advance of the lay and adapted to be moved into its path upon warp fault or failure.

From the foregoing description, it will be evident that the stop motion herein disclosed is of exceedingly simple and yet effective construction. By the elimination of springs I avoid all uncertainty of action of the parts. The dog or bunter is held stationary until warp fault or failure occurs. The single feeler cooperates with both banks of drop bars and also co-acts with a single feeler bar. The utilization of a clutch device, one part of which is mounted for sliding movement upon its support is an important feature of the invention and permits the utilization of the normally stationary dog or bunter and otherwise simplifies and renders certain the construction of parts.

Having thus described one illustrative embodiment of my invention, I desire it to be understood that although specific terms are employed, they are used in a generic and descriptive sense and not for purposes of limitation, the scope of the invention being set forth in the following claims.

40 Claims.

1. Warp stop mechanism for looms comprising in combination, a lay and shipper mechanism, indicating drop bars, a rock shaft mounted thereunder, a feeler on said rock shaft, a support distinct from said rock shaft, opposing clutch members co-axially mounted on said support, means operatively connecting said rock shaft and said clutch, a cam, and means operatively connecting said clutch and said cam and said shipper mechanism.

2. Warp stop mechanism for looms comprising in combination a lay and shipper mechanism, a bunter in the path of the lay, indicating drop bars, a rock shaft mounted under said drop bars, a feeler on said rock shaft, a support distinct from said rock shaft and mounted under said bunter, a clutch on said support, operative connections between said rock shaft and said clutch and between said clutch and said bunter, a cam, and an operative connection between said cam and said support.

3. Warp stop mechanism for looms comprising in combination, a lay, a shipper

mechanism, indicating drop bars, a rock shaft mounted under said drop bars, a feeler on said shaft, a support distinct from said rock shaft, a clutch co-axially mounted thereon and comprising a fixed member and a member slidable axially of said support, means operatively connecting said rock shaft and said support, a cam, means operatively connecting said cam and said support, and means operatively connecting said clutch and said shipper mechanism.

4. Warp stop mechanism for looms comprising in combination a lay and shipper mechanism, indicating drop bars, a rock shaft mounted under said drop bars, a feeler on said shaft, a support distinct from said rock shaft, a clutch thereon having fixed and sliding members, operative connections between said rock shaft and said support, a bunter, a lever adapted to be moved by said slidable clutch member to engage the bunter, operative connections between the bunter and shipper mechanism, a cam, and an operative connection between said cam and said support.

5. Warp stop mechanism for looms comprising in combination a lay and shipper mechanism, indicating drop bars, a rock shaft mounted under said drop bars, a feeler on said rock shaft, a support distinct from said rock shaft, a clutch thereon having fixed and slidable members, a lever having arms of which one directly engages the slidable member of the clutch and another cooperates with the shipper mechanism, operative connections between said rock shaft and said support, a cam, and an operative connection between said cam and said support.

6. Warp stop mechanism for looms comprising in combination a lay and shipper mechanism, a bunter adapted to be moved into the path of the lay, indicating drop bars, a rock shaft mounted under said drop bars, a feeler on said rock shaft, a support distinct from said rock shaft, a clutch thereon having fixed and movable members, operative connections between said rock shaft and said support, a cam shaft, a cam thereon, a lever operated thereby and connected to said slidable clutch member, and operative connections between said slidable clutch member and said bunter.

7. Warp stop mechanism for looms comprising in combination, a lay, a shipper mechanism, indicating drop bars, a rock shaft mounted thereunder, a feeler thereon, a support distinct from said rock shaft, a clutch composed of members co-axially mounted upon said support, means operatively connecting the rock shaft and said support and between said clutch and said shipper mechanism, and driven means to impart rocking movement to said clutch.

8. Warp stop mechanism for looms comprising in combination, a lay and shipper

4
1,263,896

mechanism, indicating drop bars, a rock shaft mounted thereunder, a feeler thereon, a support distinct from said rock shaft, a clutch thereon, operative connections between said rock shaft and said clutch, a cam, and operative connections between said clutch and said cam and said shipper mechanism.

In testimony whereof, I have signed my name to this specification, in the presence of 10 two subscribing witnesses.

JAMES K. LANNING.
